DESCRIPTION

Sep. 14, 2000 (JP) 2000-025746

FIG. 1 is a perspective view of a watch case with diving computer system;

(51) LOC (7) Cl. **10-02**

FIG. 2 is an alternate perspective view thereof;

(52) U.S. Cl. **D10/31; D10/38**

FIG. 3 is a front elevational view thereof;

(58) Field of Search D10/1-40, 122-132;

FIG. 4 is a rear elevational view thereof;

368/41-44, 82-84, 28-30, 239-242, 276-277,
280-282, 285

FIG. 5 is a top plan view thereof;

(56) **References Cited**

FIG. 6 is a bottom plan view thereof;

U.S. PATENT DOCUMENTS

FIG. 7 is a right side elevational view thereof;

D237,149 S * 10/1975 Watanabe D10/38

FIG. 8 is a left side elevational view thereof; and,

D339,750 S * 9/1993 Nakai D10/38

FIG. 9 is a perspective view thereof, similar to that of FIG. 1, with illustrative alpha-numeric characters and lines.

D354,242 S * 1/1995 Hanagata D10/39

The alpha-numeric characters designating time, day and date, the two lines immediately above and below the time designation, and the line immediately after the day designation of FIG. 9 are for illustrative purposes only and form no part of the claimed invention.
